[57] CLAIM

The ornamental design for a beverage cup, as shown
and described.

DESCRIPTION

FIG. 1 is a side elevational view of a beverage cup
showing my new design.

FIG. 2 is a top view thereof.

FIG. 3 is a bottom view thereof.

FIG. 4 is an enlarged fragmentary view of a portion of
the beverage cup wall of FIG. 1; and

FIG. 5 is a view in cross-section taken on line 5—5 of
FIG. 1.

FIG. 1

—FIG. 4

—FIG. 3

—FIG. 2

FIG. 5
